UNITED STATES PATENT OFFICE.

ERNEST JOHN RAWLINGS, OF LONDON, ENGLAND, ASSIGNOR TO RAWLINGS MANUFACTURING COMPANY LIMITED, OF LONDON, ENGLAND.

LATCHING AND BRAKING DEVICE FOR ADJUSTABLE WINDOWS.

Application filed December 26, 1924, Serial No. 758,279, and in France October 4, 1924.

This invention relates to latching and braking devices for adjustable windows and has particular reference to the vertically adjustable spring controlled windows of vehicles such as automobiles and railway carriages the chief object being to provide improved means for securing the window at any desired height and for preventing it from rattling.

According to the present invention one or each of the vertical limbs of the frame of the glass is formed with a row of recesses with which co-operates a spring-controlled sliding bolt or latch adapted to be mechanically withdrawn when desired by anyone wishing to adjust the window, the bolt comprising a sliding body portion formed with a recess accommodating a spring for projecting the bolt into one of the recesses and a lug co-operable with means for withdrawing the latch. Co-operating with the aforesaid bolt or latch I may also provide near one or each edge of the window a pivoted bar which is normally pressed against the edge of the window but is moved away therefrom by withdrawal of the bolt or latch. This bar when pressing against the widow serves of course as an anti-rattling and draught proof device.

In order that the invention may be clearly understood and readily carried into effect the same will now be described more fully with reference to the accompanying drawings in which:—

Figure 1 is a front elevation of part of a vehicle door having a vertically sliding glass window controlled in accordance with the present invention.

Figure 2 is a vertical sectional elevation of the parts on the line A—A of Figure 1.

Figure 3 is a sectional plan of the same on the line B—B of Figure 1.

Figure 4 is a fragmentary sectional view of the latch and associated parts in their alternative position.

Figure 5 is a fragmentary sectional view of a modified form of the latch and associated parts.

The plate glass window 1 is mounted in a frame or in vertical metal channel pieces serving as a frame. The vertical channel piece 2 shewn in the drawings is formed with a row of recesses 3 preferably in the form of triangular edge recesses (Fig. 3) with which co-operates a latch 4. The body

portion 5 of the latch is formed with a hollow central passage containing a spring 6 by which the latch as a whole is thrust towards the recesses 3.

The body portion 5 of the latch has two upstanding posts 7 and 8. The post 7 is adapted to co-operate with a lug or projection 9 on the foot of a presser bar 10 pivoted at 11 in the door frame 12. This presser bar 10 is pressed towards the vertical channel piece or framing 2 of the window by a spring 13 and is tilted away from the window when the post 7 engages the lug or projection 9.

The spring 6 in the latch and the spring 13 in the presser bar are provided with plunger-like bearing pieces 14 and 15 respectively which bear against a facing piece 16.

The post 8 on the body portion of the latch is located to be engaged by a crank or arm 17 on a transversely extending rod 18 adapted to be turned angularly by means of a finger piece or handle 19 at the centre of the door.

20 is a spring barrel and 21 is a cord by which the window is automatically raised when released.

The operation of the mechanism is as follows:—Assuming that the parts are in the position shown in Figures 1 and 2 and that it is desired to raise or lower the window, the handle 19 is raised, thereby rocking the rod 18 and causing the crank or arm 17 to bear against the post 8 and push back the body portion 5 and latch proper 4 against the pressure of the spring 6. As soon as the latch is free from the recess 3 in which it was housed, the further retractive movement of the latch body causes the post 7 to engage the lug or projection 9 and thereby rock the presser bar 10 away from contact with the vertical channel piece 2 (Fig. 4). If no hand control is applied to the window itself, the window will now travel upwards under the driving force of the spring in the barrel 20. Alternatively if hand pressure is put upon the window it can be lowered to any desired degree against the force of the spring in the spring barrel.

Immediately the handle 19 is lowered the presser bar 10 and latch 4 return to their operative positions.

It is important to observe that owing to the positive engagement of the latch 4 in the

5 recesses 3 it is not possible for the window to "creep" upwards, nor can downward pressure, such as by a passenger leaning over the window, cause it to become lowered. More-
10 over the presser bar 10 exerts a well distributed edge pressure on the channel piece 2 and thereby prevents rattling of the window in the door frame, and serves to keep out draughts.

15 10 Obviously the latch and presser bar arrangement is preferably provided at both of the vertical edges of the window.

15 In a simplified constructional form of the invention shown in Fig. 5 which is a fragmentary vertical sectional view comparable with Fig. 2, the body portion of the latch has only one upstanding post 7' which is so located as to be engaged by a crank or arm 17', and is so disposed that in operation 20 after the latch has been withdrawn sufficiently to be free from the recess in which it was housed, further retractive movement of the latch body causes the said post 7' to engage a lug or projection 9' on the presser 25 bar 10 and thereby to rock the latter away from contact with the window glass frame.

What I claim is:—

1. A latching device for adjustable windows comprising a spring controlled sliding latch, a movable window frame formed with 30 a row of recesses to accommodate the latch, the latch comprising a sliding body portion formed with a recess, a spring accommodated in said recess for projecting the latch into one of the said recesses, a lug on said 35 body portion, and means for withdrawing the latch co-operating with said lug.

2. In a latching and braking device for windows a braking device normally engaging said window, a latch comprising a body 40 portion and a latch portion, means for guiding said latch in its reciprocating movements, means for urging said latch in one direction to lock the window, means operable at will for urging said latch in the opposite 45 direction, a post on the body portion of said latch, and a projection on said braking device normally spaced from said post but engaging therewith to retract said braking device from the window when said latch is 50 moved sufficiently in said opposite direction.

ERNEST JOHN RAWLINGS.
